UNITED STATES PATENT OFFICE

2,426,562

BOXCAR UNLOADER

Henry G. Onstad, Chicago, Ill.

Application June 7, 1945, Serial No. 598,037

1 Claim. (Cl. 214—44)

1

This invention relates to unloading apparatus, and although it has been designed primarily for unloading grain from box cars, it is also adaptable, with slight variations in detail, for unloading cement, coal, soda ash or other free flowing granular materials, and can also be used for other purposes, such as moving free flowing materials from storage piles and other handling equipment, and moving materials in the holds of vessels to marine unloading equipment.

One of the objects of this invention is to provide a simple, practical and efficient unloading apparatus embodying a dirigible self-propelled unloader having a conveyor arranged to convey the material towards a discharge opening in a railway car or other conveyance, and also functioning to propel the unloader.

Another object is the provision of steering means controlled from the outside of the railway car, whereby the unloader can be guided to travel in any direction.

Another object is the provision of an unloader having an endless conveyor, provided with rubber or other flexible flight or blades arranged to engage the surface upon which the unloader is moved, and to engage the material and convey it towards a discharge opening.

With these and other objects and advantages in view, this invention consists in the several novel features of construction, arrangement and combination of parts hereinafter fully described and more particularly defined in the appended claim.

The invention is clearly illustrated in the drawings accompanying this specification, in which:

Fig. 1 is a diagrammatic view partly in plan and partly in horizontal section illustrating one embodiment of the unloading apparatus in use unloading a railway car and showing the unloader in dotted lines and in dot-dash lines in two positions;

Fig. 2 is a vertical cross section taken on the line 2—2 of Fig. 1;

Fig. 3 is an enlarged, central, vertical, longitudinal section through the unloader;

Fig. 4 is a vertical cross section taken on the line 4—4 of Fig. 3; and

Fig. 5 is a wiring diagram illustrating the circuits for the motors.

Referring to said drawings, which are merely illustrative of one embodiment of the invention, the unloading apparatus comprises an unloader 10, steering cables 11, 12 attached to the unloader 10, and trained around portable snatch blocks 13, 13a and carried by the frame work of a railway car 14

2

and disposed adjacent the door openings 15, 16 thereof. The door opening 16 is shown as closed by a temporary wall 17 and the door opening 15 is shown open for the discharge of the material.

5 At the unloading station, a platform 18 is provided, which has a clear space upon which the unloader may be driven. Connecting the platform with the side of the railway car is a movable platform 19 over which the unloader may travel from the platform to the interior of the railway car. The platform and floor of the railway car are substantially on the same level. The auxiliary platform 19 may be laid on the main platform and the railway car floor, or it may be supported in any suitable manner.

Extending through the platform and projecting above the same is a post 20, here shown in the form of an I beam, and on this post are secured horizontal structural members, such as channel members 21 for supporting a platform 22, upon which are mounted two winches 23, 24. The cables 11, 12 are wound upon the drums of the winches and are trained around other sheaves 25, 25a carried by the platform at places adjacent the top thereof, from which the cables run to the snatch blocks and thence to the unloader.

20 Mounted on the post adjacent the channel members 21 is a bracket 27 upon which is rotatably mounted a spring return reel 28, around which is wound an electrical control cable 29 which runs to the unloader, and is connected to a source of electrical energy in any approved manner.

25 The unloader is best seen in Figs. 3 and 4 and comprises, among other things, a housing composed of upright side walls 31 connected to an inverted V-shaped top wall 32, as by angle irons 33. Upon the top wall of the unloader are secured two eyes 61, 62 to which the steering cables are attached. Bolted or otherwise secured to angle irons 34 fastened to the inner faces of the side 30 walls are planks 35, 36 which extend across the housing adjacent its lower end and support the motor 37 and its speed reducing gearing 38. The motor is connected to the speed reducing gearing by a shaft coupling 39. It may be here stated 35 that the motor 37 is a reversible motor whereby the unloader may be propelled forwards or backwards. The power cable 29, heretofore referred to, leads to and is connected to the motor 27. In the 40 housing is a traveling endless conveyor which propels the unloader and conveys the material to one end thereof.

An inner housing composed of a top wall 40 and of inverted V-shape, a bottom wall 40a, and two 45 end walls 41 encloses the motor and speed reduc-

ing gearing. The walls of the inner housing may extend to and be secured to the side walls 31 of the outer housing by angle irons or otherwise as is desired. The inner housing protects the motor and speed reducing gearing from the material which is being unloaded.

Upon the drive shaft of the speed reducing gearing is a sprocket wheel 42 which is connected to a sprocket wheel 43 by a sprocket chain 44. The sprocket wheel 43 is mounted upon a shaft 45 journaled in bearing boxes 46 carried by the side walls of the outer housing, and mounted upon said shaft 45 are two sprocket wheels 47 disposed adjacent the side walls of the outer housing, and trained around said sprocket wheels 47 are sprocket chains 48. The sprocket wheels 47 form the driving means for the sprocket chains 48. A hood 64 extending up from the top wall 40 of the inner housing encloses the sprocket wheel 43 and the part of the sprocket chain 44 which runs above the top wall 40.

Adjacent the bottom of the outer housing are two idler sprocket wheels 49, 50 around which the sprocket chains 48 are trained. The axes of these sprocket wheels 49, 50 are horizontally aligned and said sprocket wheels may be mounted upon shafts in the same manner as the sprocket wheels 47 are mounted.

Secured to and carried by the sprocket chains 48 are conveyor flights 51 which extend crosswise of the outer housing and are made of such width that when traveling between the sprocket wheels 49, 50 they bear upon the surface upon which the unloader is supported with sufficient pressure to obtain traction for propelling the unloader.

While the exact construction of the flights is immaterial to this invention, broadly considered, they are here shown as formed of transversely extending slats or bars 52 secured to links of the endless sprocket chains 48, and angle plates 52a secured to the slats or bars with rubber or other flexible flight blades 53 secured between the angle plates 52a by rivets or the like. Lengthwise extending guide bars 54, 54a are secured to the angle irons 34, 55 above and below the slats or bars 52 and serve to guide the slats or bars during their movement between the sprocket wheels 49, 50. Other guide bars 52b paralleling the oblique portions of the conveyor may be provided if desired.

Caster wheels 56 mounted in brackets 56a secured to the ends of the outer housing comprise the direct support for the unloader. The caster wheels are vertically adjustable as by threaded stems 58 and nuts 58a thereon and carried by angle irons 60 which are secured to the ends of the outer housing. The caster wheels enable the housing to be moved forwards or backwards or to be turned.

The vertical adjustment means for the caster wheels is provided to compensate for wear on the edges of the flights and to control the pressure of the flights on the surface on which they operate, which pressure, together with the operation of the conveyor, makes the unloader self-propelling, and with the reversible movement of the motor it can travel forwards or backwards at the will of the operator.

A remote control panel 61, provided with suitable push buttons or switches, is connected by an electric cable to the power cable whereby the attendant may control the operation of the unloader.

Preferably the winches 23, 24 are operated by reversible motor 23a, 24a and if desired reversi-

ble control switches for the motors of the winches may be included in the remote control panel for starting, stopping and reversing the operation of the motors of the winches.

In Fig. 5 is illustrated a wiring diagram for the motors. As shown, the power lines 66, 67 from the source of electricity connect with the power cable 29 through a pole changer or reversing switch 68 and through lines 69, 70 to two stationary contact rings 71, 72 contiguous with the drum of the reel 28, which contact rings contact with contact pieces 73, 73a insulated from the drum of the reel and forming the terminals of the two lines of the power cable 29. Lines 74, 75 run from the main lines 66, 67 through a reversing switch 76 to the motor 23a of the winch 23 and lines 77, 78 run from the main lines through a reversing switch 79 to the motor 24a of the winch 24.

In the operation of the unloading apparatus, one of the side doors of the car is opened and the temporary wall behind the door opening is removed, permitting some of the contents of the car to discharge by gravity through the door opening. At this time the unloader stands on the platform 18. The switch controlling the motor of the unloader is then closed, thereby starting the motor and driving the unloader in a direction towards the door opening of the car. Traction is obtained by the engagement of the flights with the platform. The steering cable 12 may be trained around the snatch block 13a and attached to the eye 62 on the unloader and the winch 24 started, whereby to pull the front end of the unloader toward the door opening. Or a guide rail 70 may be provided on the platform for guiding the unloader through the door opening of the railway car. The caster wheels will then be caused to travel along the guide rail. When the unloader has entered the car, the steering cables 11, 12 are passed around the snatch blocks 13, 13a and fastened to the eye 61 on the unloader, and the auxiliary platform is removed.

As the flights of the unloader engage the material in the car they propel the material backwards towards the door opening. It is possible for the unloader to climb upon the material in the car, but in doing so it also propels the material backwards to an end of the unloader. By properly manipulating the winches 23, 24, the pull upon the unloader may be exerted to restrain its traveling movement and to turn it in almost every direction. In this manner the unloader may be caused to move to all parts of one end of the railway car. Some of the material is moved to the door opening by pulling the unloader back by one or the other of the cables 11, 12. When one end of the car has been cleared of the material, the unloader is drawn back by the winches and steering cables, or the direction of rotation of the motor is reversed so as to cause the endless conveyor to propel the unloader toward the other end of the car. The snatch blocks 13, 13a are then transferred to hooks or eyes 13b located at the other side of the door openings and the steering cables are then attached to the other eye 62 and the procedure above described is repeated. When all of the material has been unloaded, the auxiliary platform is replaced and the unloader may then be driven back on the platform.

When used to unload grain or other free flowing material from railway cars having a trap door in the floor for discharging the materials, the same procedure is carried on, except that the

unloader is steered toward and away from the discharge opening in the floor whereby to discharge the material therethrough.

Having thus described my invention, it is obvious that various modifications may be made in the same without departing from the spirit of my invention; hence I do not wish to be understood as limiting myself to the exact form, arrangement and combination of parts herein shown and described or uses mentioned.

What I claim as new and desire to secured by Letters Patent is:

In an unloading apparatus, an unloader comprising a housing, caster wheels supporting said housing, an endless conveyor in said housing having flights arranged to bear upon the surface on which the unloader is driven, said conveyor functioning to propel the unloader and to convey materials to an end thereof, a motor mounted in said housing, drive connections between said mo-

tor and conveyor, snatch blocks attached to the opposite side walls of a vehicle in which the unloader is being used, steering cables attached to the unloader and trained over said snatch blocks, and winches for the cables for controlling the speed of the unloader and for restraining the traveling movement thereof.
